GAME BOARD

Elliot J. Grosberg, 862a Longacre Drive,
St. Louis, Mo. 63132

Filed Aug. 7, 1967, Ser. No. 8,145

Term of patent 3½ years

(Cl. D34—5)

FIG. 1

Conventional legible matter is shown in broken lines.
I claim:

The ornamental design for a game board, substantially as shown and described.
